Primary Examiner — Dana K Weiland*Assistant Examiner* — Emily Anna Saunders(74) Attorney, Agent, or Firm — Fish & Richardson P.C.(57) CLAIM

The ornamental design for a sink toy, as shown and described.

DESCRIPTION

FIG. 1 is a perspective view of our sink toy.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The broken lines in the drawings depict portions of the sink toy that form no part of the claimed design.

1 Claim, 4 Drawing Sheets(56)
